TREATMENT OF OIL WELLS TO PREVENT
EMULSIFICATION

Gale L. Adams, San Marino, and Abraham Shapiro, Monrovia, Calif., assignors to Socony-Vacuum Oil Company, New York, N. Y., a corporation of New York

No Drawing. Application March 11, 1941,
Serial No. 382,781

4 Claims. (Cl. 252—8.55)

The object of the invention is to eliminate, or to reduce to an important extent, the amount of emulsion produced in pumping oil wells which yield hard waters along with the oil.

It is well known that oil wells which produce alkaline waters along with the oil are apt to yield an oil containing a highly refractory emulsion, which is difficult to resolve and separate after the oil has been brought to the surface. It is also known that the emulsions so formed are refractory because they are stabilized by salts of magnesium and calcium with certain organic acids (e. g., naphthenic acids) which are commonly present in the crude oil.

It has been proposed to introduce water softening agents into such wells, to combine with the alkali earth metals of the water and so prevent the type of emulsion due to these metallic soaps. Such proposals, however, have been limited to the use of alkaline reagents such as the alkali metal carbonates and silicates and neutral salts such as the alkali metal sulfates and, by reason of the low order of effectiveness of these materials, such treatments have not given satisfactory results nor come into practical use.

We have discovered that the various alkali metal phosphates are more suitable for this purpose than the salts heretofore used, and that the disodium phosphate (Na_2HPO_4) is particularly efficacious. We have also discovered that the efficiency of the phosphate in preventing the formation of tight emulsions is greatly increased by the simultaneous addition to the well of a free acid, preferably sulfuric acid, in quantity sufficient to bring the water produced with the oil to a pH within the range pH 6.5 to pH 7.4. Within this range the sulfuric acid precipitates any barium present in the water as the very insoluble sulfate, while the phosphate salt precipitates the calcium, magnesium, iron, and aluminum in a flocculent gelatinous form.

In the practical application of the invention a sample of the water produced by the well is tested for its pH value, and the quantity produced daily is determined. A solution of a sodium or potassium phosphate is then prepared, acidulated with a mineral acid (preferably sulfuric acid) and fed into the casing of the well in a controlled stream. The rate of introduction is so regulated, and the composition of the stream so adjusted, that the quantity of acid so added will bring the pH of the produced water to a value as close to 7.0 as possible, and within the range pH 6.5 to pH 7.4, and that the quantity of the phosphate is sufficient substantially to precipitate the

5 soap-forming alkali earths and heavy metals. This latter quantity may be predetermined in a preliminary titration of the water with a standardized phosphate solution, or it may be controlled while feeding the solution by observing the condition of the oil-water mixture produced by the well. When using sodium diphosphate the quantity required may be from 1 part salt to 1000 parts water upwardly, according to the initial hardness of the water.

10 The product from the well during this treatment may consist of free water and relatively water-free oil, or the water may be suspended in the oil and lightly emulsified. In the latter case it will be found that the emulsion is not refractory and that it will break and permit the water to be separated by simple settling at a temperature at which the oil is fully liquid.

15 It will be found that the oil resulting from this settling or other physical method of separating the oily from the aqueous phase will be substantially free from calcium and magnesium chlorides, the admixture of the treated water with the oil in the pump and the delivery tubing being ordinarily sufficient to bring the solution into contact with the suspended particles and thus precipitate these metals as phosphates.

20 The same treatment may be applied to the removal of these corrosive chlorides from crude oils 30 to be refined by distillation. In this treatment the oil is agitated and emulsified with a dilute aqueous solution of an alkali metal phosphate, preferably disodium phosphate, previously adjusted to about pH 6.5 by the addition of sulfuric acid. The thus produced emulsion is then settled and it will be found that the supernatant oil is 35 substantially free from the chlorides of calcium and magnesium which unless removed are highly corrosive to refinery distillation and condensing equipment.

40 We claim as our invention:

1. In a method of treating an oil well normally producing hard water along with the oil which includes introducing into said well a stream of 45 an aqueous solution, the improvement which comprises: using a solution of an alkali metal phosphate acidulated with a mineral acid as said introduced stream; and so controlling the composition and volume of said introduced stream as to bring the water produced from said well to a pH value within the range from 6.5 to 7.4 and to precipitate at least a portion of the alkali earth metal and heavy metal constituents of said water as gelatinous phosphates.

50 2. A method substantially as and for the pur-

pose set forth in claim 1 in which said alkali metal phosphate is disodium phosphate.

3. A method substantially as and for the purpose set forth in claim 1 in which said mineral acid is sulfuric acid.

4. The method of freeing crude petroleum from calcium and magnesium compounds which comprises admixing said petroleum with an aqueous solution of an alkali metal phosphate acidulated with a mineral acid, the composition and quan-

5. tity of said aqueous solution being so regulated as to bring the pH value of the water contained in said admixture to a pH value within the range 6.5 to 7.4, and to precipitate a desired proportion of said calcium and magnesium compounds as phosphates, and physically separating the aqueous from the oily phase after said admixture.
